UNITED STATES PATENT OFFICE.

WILLIAM HICKS CURTICE, OF LOUISVILLE, KENTUCKY.

CONVERTIBLE FURNITURE.

1,077,189.

Specification of Letters Patent. Patented Oct. 28, 1913.

Application filed March 14, 1913. Serial No. 754,320.

To all whom it may concern:

Be it known that I, WILLIAM HICKS CURTICE, a citizen of the United States, residing at Louisville, in the county of Jefferson and 5 State of Kentucky, have invented new and useful Improvements in Convertible Furniture, of which the following is a specification.

The present invention has reference to 10 convertible furniture, and it proposes, briefly, an improved article of furniture which may be utilized either as a chair or as a table, and which may be readily converted from either of such forms to the other.

15 More particularly, the invention comprehends certain hereinafter-specified improvements in the devices employed for connecting the movable part to the stationary part or body, these devices serving to guide the 20 first-mentioned part during its movements and to support the same when occupying one of its two positions.

An embodiment of the invention is illustrated in the accompanying drawing, where- 25 of:—

Figure 1 is a perspective view of the improved article of furniture used as a chair; Fig. 2 is a vertical section on line 2—2, Fig. 1; Fig. 3 is a vertical sectional view, 30 showing the article of furniture converted into a table; and Fig. 4 is a fragmental vertical sectional view, showing the movable part during its travel from one position to the other.

35 As shown in said drawing, the article of furniture consists of two main parts, one of which, generally designated by the reference numeral 5, is stationary and constitutes the body, while the other part 6 is movable and 40 serves either as the chair back or the table top, according as it occupies one or the other of its two positions. The part 5 is in the main, of conventional construction and embodies the front and rear legs 7 and 8, the arms 45 9, and the seat 10, the part last mentioned having a sliding drawer 11 of suitable type connected with it.

The movable part 6, which may be given any desired shape, is flat, as shown, and is 50 provided upon its front face with a pair of spaced, parallel cleats 12 that are so arranged as to rest directly upon the arms 9, when the article of furniture is to be used as a table, and that abut against the rear 55 ends of the aforesaid arms when the article is converted into a chair. In the latter use,

the part 6 occupies a substantially vertical position, and the rear end of the seat 10 fits between the lower ends of the aforesaid cleats, whereby the said part is braced 60 against sidewise movement. The space between the cleats may be utilized to receive a cushion 13, and the seat 10 may likewise be upholstered, as indicated by the numeral 14, the cushion 13 being removably secured 65 to part 6 by means of perforated straps 15, or other suitable devices which are engaged with headed pins 16 driven into said part. The part 6, which thus constitutes both the 70 chair back and the table top, is positively connected with the stationary part or body 5 by pairs of main and auxiliary links 17 and 18. The main links 17 are curved, as shown, and are pivoted at one end in the rear ends of a pair of longitudinal slots 19 formed in 75 the arms 9, and at the other end in a pair of slots 20 formed in the cleats 12, suitable cross-pins 21 and 22 being passed through said slots for the attachment of the links thereto. The auxiliary links 18 are pivoted 80 at their opposite ends to cross-pins 23 and 24 which are arranged, respectively, in slots 25 and 26 formed in the rear legs 8 and the lower or rear portions of said cleats. During the movement of part 6 from vertical 85 to horizontal position, the main links 17 swing into and through the arm slots 19, while the auxiliary links 18 are swung from a position in the lower end of the leg slots 25 to one in the upper end thereof, as will 90 be understood, the reverse taking place when said part is moved into vertical position, and at the completion of the former movement the cleat slots 20 lie directly over and in line with the front ends of said arm slots. The 95 links 18, owing to the formation of the slots 25 in the rear portions of the legs, are concealed in both positions of the movable part 6, these slots being continued upwardly 100 through the rear ends of the arms, as indicated by the numeral 27.

The operation in converting the article from a chair to a table, and vice versa, is believed to be apparent, and, hence, to require no separate explanation.

105

Having described my invention, I claim:—

A convertible article of furniture comprising fixed and movable parts, the former of which embodies a seat, front and rear pairs of legs connected thereto, and arms 110 connected to the upper ends of said legs, said arms being formed, each, with front and rear

slots, the latter of which open through the rear ends of the arms, and the rear pair of legs being formed with vertical slots which register at their upper ends with the rear slots in said arms; a pair of spaced, parallel cleats secured to the under face of the movable part, and formed, each, with front and rear slots, said cleats being adapted to rest directly upon said arms when said movable part is in one position and to abut against the rear ends of said arms when said movable part is in its other position; a pair of main links pivoted at one end in the front slots in said cleats, and at the other end in the front slots in said arms; and a pair of auxiliary links pivoted at one end in the

rear slots in said cleats and at the other end in the slots in said legs, said main links being arranged to lie in said front arm slots, and said auxiliary links to lie in said leg 20 slots with their upper ends projecting through the rear slots in said arms, when said movable member is in the second-named position.

In testimony whereof I have hereunto set 25 my hand in presence of two subscribing witnesses.

WILLIAM HICKS CURTICE.
